UNITED STATES PATENT OFFICE.

GEORGE FRICK AND EDGAR PENNEY, OF WAYNESBOROUGH, PA.

FEED MECHANISM FOR SAW-MILLS.

SPECIFICATION forming part of Letters Patent No. 355,071, dated December 28, 1886.

Application filed June 17, 1886. Serial No. 205,465. (No model.)

To all whom it may concern:

Be it known that we, GEORGE FRICK and EDGAR PENNEY, citizens of the United States, residing at Waynesborough, in the county of 5 Franklin and State of Pennsylvania, have invented certain new and useful Improvements in Feeding Mechanism for Saw-Mills; and we do hereby declare the following to be a full, clear, and exact description of the invention, such as 10 will enable others skilled in the art to which it appertains to make and use the same.

This invention relates to the feed mechanism of that type of circular saw mills in which the power is derived from the saw-arbor 15 through friction-gearing.

Our improvement consists of certain combinations, each one of which is specified by a separate claim at the close of this specification. Less than the whole number of these 20 combinations may be used; but the best results are obtained where all are used.

In order that our invention may be clearly understood, we have illustrated in the annexed drawings, and will proceed to describe, a practical form thereof.

Figure 1 represents a plan view of so much of a circular-saw mill as suffices to illustrate the application of our invention. Fig. 2 also represents a plan view, but where some parts 30 shown in Fig. 1 are omitted, and others are broken away. Fig. 3 represents a longitudinal section in the plane indicated by broken line $x\ x$ on Fig. 1. Fig. 4 represents a cross-section in the plane indicated by broken line $y\ y$ on Fig. 1. Fig. 5 represents a cross-section in the plane indicated by broken line $z\ z$ on Fig. 1.

The same letters of reference indicate identical parts in all the figures.

The feed-shaft 10 is driven from the friction-hub 2^a of a duplex friction driving-pulley, 2, on the saw-arbor 1 to feed the carriage, and from the internal friction surface or ring, 2^c, of the rim of said pulley to gig the carriage back 40 through the intervention of the friction-pinion 3 on one end of parallel shaft 4, friction-disk 5 on said shaft, friction-wheel 6 on cross-shaft 7, bevel-wheel 8 on said cross-shaft, and bevel-wheel 9 on the feed-shaft. Parallel shaft 4 is 45 supported in bearings across a frame, 11, hinged at one end on feed-shaft 10, and so sus-

pended at the other end that it can be turned to throw the friction-pinion 3 either out of contact or into contact with the friction-hub 2^a, or with the internal friction-ring, 2^c. The 55 hinged frame is suspended at one side by a suspension-link, 12, from a crank-pin, 13^a, of crank-disk 13 on rock-shaft 14. The canting strain put on parallel shaft 4 is compensated, as regards the hinged frame, by suspending 60 said frame at its other side by a suspension-link, 15, from one arm of a compensating lever, 16, a slot, 16^a, in the other arm of which engages a crank-pin, 13^b, on crank-disk 13, diametrically opposite to crank-pin 13^a and on 65 the reverse outer side of said disk. The compensating lever is fulcrumed on a fixed bracket-arm, 17. The suspension-link 15 consists of two rods connected by a nut, 15^a, with right and left threads, so that its length may be accurately adjusted.

Rock-shaft 14, supported in suitable fixed bearings, is provided, at the most convenient point for the operator, with a hand-lever, 18, which is cross-pivoted to the sleeve 18^a, by 75 which it is secured to said shaft. By turning said lever crosswise of the rock-shaft the latter can be rocked to turn crank-disk 13 for the purpose of raising or lowering the suspended end of the hinged frame, and throwing the 80 friction-pinion in or out of gear. This hand-lever is cross-pivoted on its sleeve, in order that it may also be used for operating the shifter-rod 19, one end of which is connected by a link, 19^a, to said lever between broad 85 cheeks 18^a thereof, while the other end is connected with or engages a groove in the hub of friction-wheel 6. By turning the hand-lever on its cross-pivot—*i. e.*, lengthwise of the rock-shaft—the friction-wheel 6 can be shifted along 90 the face of the friction-disk 5, to change at will the speed imparted to said friction-wheel by said friction-disk. The friction-wheel is connected to its shaft by a groove and long spline, so that it may be slid, as required.

An adjustable collar, 7^a, is placed on cross-shaft 7, to limit the shifting of the friction-wheel in one direction, it being limited in the other direction either by the out-bearing 11^a of parallel shaft 4, or by some other suitable 100 means. Bearing 7^a at one end of cross-shaft 7 is vertically pivoted at 11^a between bracket-

arms 11^a of hinged frame 11, and bearing 7^a at the other end of said cross-shaft is horizontally pivoted at 11^b between cheeks 11^d of the hinged frame, so that the said shaft may have sufficient lateral motion to throw friction-wheel 6 into firm contact with friction-disk 5, or out of contact. Bearing 7^a has a lever-arm, 7^c, which projects up by the side of a vertical flange, 13^a, on crank-disk 13. Flange 13^a has two set-screws, one, 13^b, above the center of the disk, and another, 13^c, below the center of the disk. These set-screws are so adjusted that either the one or the other presses against lever arm 7^c, forcing friction-wheel 6 firmly against friction-disk 5 whenever friction-pinion 3 is driven; but when the friction-pinion is not running, then lever-arm 7^c is relieved from both set-screws, and the pressure between the friction-wheel 6 and friction-disk 5 suspended, so that indentation or flattening of the friction-surfaces is prevented. By means of these set screws the wear between friction-disk 5 and friction-wheel 6 can also be taken up.

We prefer to counterbalance the hinged frame and its appurtenances, as shown.

It will be observed that the single hand-lever 18 gives the operator complete control over the feed mechanism, not only for instant reversal, but also for instant change of speed and simultaneous separation or relief of pressure between the several friction surfaces.

We claim as our invention—

1. The combination, with a shaft provided with a duplex driving-pulley, of the feed-shaft, a frame pivoted on the feed-shaft and having its free end extending on one side of the duplex pulley-shaft, and a shaft mounted on said frame parallel with the pulley-shaft and provided with a friction-pinion, substantially as described.

2. The combination, with a shaft provided with a duplex driving-pulley, of the feed-shaft, a frame pivoted on the feed-shaft and extending on one side of the duplex pulley-shaft, a shaft mounted on said pivoted frame parallel with the pulley-shaft, provided with a friction-pinion, and a shaft having a crank-and-link connection with the pivoted frame, substantially as described.

3. The combination, with a pivoted frame, of a shaft located above and parallel to one side of said frame, a crank, a link connecting said crank to one side of the pivoted frame and a crank on the opposite side of said shaft, and a compensating lever and link connecting said crank and the other side of said frame, substantially as described.

4. The combination, with the pivoted frame, of a shaft located above and parallel with one

side of said frame, a crank-disk attached thereto and provided with crank-pins at opposite sides of the same, a link attached to one of said crank-pins and connected to the pivoted frame, and a lever connected with the other crank-pin and with the other side of the frame, substantially as described.

5. The combination, with the main shaft provided with a duplex driving-pulley, the feed-shaft, the frame, the pivoted frame having its free end extending to one side of the main shaft, a shaft parallel with the main shaft and mounted on the said pivoted frame, having a friction-pinion and friction-disk, of a shaft at right angles to the main shaft mounted on the pivoted frame and provided with a friction-wheel, and the bevel-wheels on the shaft at right angles to the main shaft and the feed-shaft, substantially as described.

6. The combination, with the feed-shaft and the main shaft having the duplex friction driving-pulley, of a pivoted frame having its free end extending on one side of the said main shaft, a shaft parallel with said main shaft mounted on said pivoted frame and provided with a friction-pinion and a friction-disk, a shaft mounted on the pivoted frame and having a movable friction-wheel at one end and operatively connected with the feed-shaft at the other, a rock-shaft having a crank-and-link connection with the pivoted frame, a cross-jointed hand-lever on said rock-shaft, and connected with the movable friction-wheel, substantially as described.

7. The combination of the feed-shaft and main shaft having the duplex friction driving-pulley, a frame hinged on the feed-shaft and having its free end extending on one side of the main shaft, a shaft parallel with the main shaft mounted on said hinged frame and having a friction-pinion and friction-disk, a shaft mounted on said hinged frame at right angles to the main shaft and having a friction-wheel at one end and operatively connected with the feed-shaft at its other end, and a rock-shaft having a crank-and-link connection with the hinged frame, having a vertical flange with two diametrically-opposite set-screws, the said shaft at right angles to the main shaft being mounted in movable bearings, one of which has a lever-arm extending into the path of the set-screws, substantially as described.

In testimony whereof we affix our signatures in presence of two witnesses.
